CLAIM

The ornamental design for a towel bar mounting post,
as shown and described.

DESCRIPTION

FIG. 1 is a side elevational view of a towel bar mounting post showing our new design;

FIG. 2 is a top plan view thereof, the bottom being a mirror image;

FIG. 3 is an opposite side elevational view thereof;

FIG. 4 is a front elevational view thereof;

FIG. 5 is a rear elevational view thereof; and,

FIG. 6 is a horizontal cross-sectional view thereof,
taken along line 6—6 of FIG. 3.

FIG. 1.

FIG. 2.

FIG. 3.

FIG. 4.

FIG. 5.

FIG. 6.
